UNITED STATES PATENT OFFICE.

VITTORIO CASOLETTI, OF TURIN, ITALY.

APPARATUS FOR WASHING CUPS, GLASSES, AND THE LIKE.

Application filed January 29, 1926, Serial No. 84,627, and in Italy February 4, 1925.

This invention has for its object to provide an apparatus for washing and disinfecting cups, glasses and the like and is chiefly characterized by the fact that said operations are effected by means of water jets thrown with force and carrying along heavy bodies, for instance lead or steel or brass or aluminum or glass balls; said bodies, thus thrown at a high speed, strike against and clean the walls against which they are thrown.

This invention has further for its object to provide suitable means for discharging the water, while the balls are collected and returned into the projecting conduits, wherefrom they are again carried along by the water.

The apparatus forming the object of this invention is shewn on the annexed drawings, in which:

Fig. 1 is an axial vertical section.

Fig. 2 is a section on a vertical plane displaced through 45° with respect to the section shewn in Fig. 1.

Fig. 3 is a section similar to Fig. 2 showing on an enlarged scale the apparatus in the working position.

A funnel-shaped receptacle 1, preferably of sheet iron, is provided with openings 2, the width of which is less than the diameter of the balls 30, contained in the receptacle. The receptacle 1 is provided with grooves 3 of U-section and is suitably curved at its upper edge for the purpose hereinafter explained.

The receptacle 1 carries a central piece hung by means of hooks 4 and rings 5, 5' and constituted by two annular members 6 arranged in different horizontal planes and connected by means of ribs 7 the lower annular member having a central collar 8 constituting a funnel.

The suspension ring 5' is connected with the stem 9 of a valve 10 arranged in a casing 11 and closing a discharge opening provided in said casing when said valve is raised by means of two springs 12 and 13.

The casing 11 communicates through a tube 14 with another casing subdivided into two compartments 15 and 20 by means of a flexible diaphragm 16. The upper compartment 15 constitutes a pressure chamber, the lower compartment 20 contains a central conduit 17 fed by a water conduit through a filter 18.

The compartment 20 communicates with a conduit 21 ending with a central nozzle 22

and side nozzles 23 corresponding to grooves 3 of the receptacle 1, the conduit 21 constituting the central supporting pillar thereof.

The conduit 17 forms in the compartment 20 an annular chamber and communication between the latter and the conduit 17 is controlled by the diaphragm 16 the movement of which is controlled as hereinafter described by the operation of the valve 10. The diaphragm 16 has mounted centrally therein a throttling valve 19 formed with a guide stem which extends below the diaphragm into the conduit 17 and said valve and stem have an axial passage 19' through which communication between said conduit and the pressure chamber 15 is constantly maintained. After the valve 10 has been closed, the water in conduit 17 will continue to flow through passage 19' until the pressure on both sides 75 of the diaphragm becomes the same, so that the weight of the valve stem on the underside of the diaphragm will cause the latter to seat on the end of the conduit 17 and close communication between the conduit and the 80 annular chamber 20.

The apparatus comprises further a protecting casing 24, a casing 25 and a sleeve 26 arranged at its upper part and preferably of glass. At the upper part of the apparatus a circular spraying arrangement will be conveniently disposed and fed by a tube 27' carried by the conduit 21.

The apparatus works as follows:

When the cup or glass rim is pressed 90 against the supporting piece 6, 7, this latter, by means of the ring 5', causes the stem 9 of the valve 10 to oscillate, so that the valve, coming into an inclined position with respect to its seat, allows the water to escape 95 from the casing 11 and therefore from the compartment 15, in which the pressure is thus nearly completely annulled.

The counterpressure being relieved from the flexible diaphragm 16, this latter is raised 100 by the water pressure on the underside of the diaphragm and opens a free passage to the water from the conduit 17 to the compartment 20 and conduit 21. Strong water jets are projected through the nozzles 22 against 105 the cup or the like to be washed inside the same. The water in conduit 21 also issues from the diagonally arranged nozzles 23 into the grooves 3 from which the water together with the balls 30 are discharged against the 110 outside of the cup or the like at the mouth or rim of the latter. This is accomplished by

the rim of the receptacle 1 being inwardly and downwardly turned towards the mouth of the cup.

The balls 30, carried along by the water, are violently projected against the glass walls and fall again into the receptacle 1 and are collected at the central part thereof and brought again into circulation by the water jets. The water is collected in the casing 24 and discharged therefrom.

In this way a perfect washing of the glass is obtained and completed by a washing of the outer upper part by providing a circular jet 27.

15 In order to prevent any ball from getting behind the stem 9 thus preventing a perfect closure of the valve, the stem is provided with a plate 9¹ fitting in the opening of the receptacle 1 through which the stem 9 projects. Said plate expels from said opening the balls that may have eventually stopped therein.

20 The feeding tubes will be conveniently provided with an expansion chamber in order to damp the water hammer taking place when the water circulation is suddenly stopped after the glass has already been taken away from the supports 6, 7.

What I claim is:

30 1. An apparatus for washing open receptacles, comprising a water supply conduit, a nozzle communicating with the latter for directing a jet of water into the receptacle, laterally arranged nozzles communicating 35 with the supply conduit, means to conduct jets of water from the lateral nozzles onto the exterior of the receptacle, a pressure conduit, a flexible partition or diaphragm interposed between the pressure and supply 40 conduits, a pressure chamber above the diaphragm, a throttle valve in the latter having a passage connecting the pressure chamber and pressure conduit to equalize the pressures on both sides of the diaphragm, and 45 means to reduce the pressure in the pressure chamber to automatically open the pressure conduit.

2. Apparatus for washing open receptacles, comprising a water supply conduit, a nozzle communicating with the latter for directing a jet of water into the receptacle, laterally arranged nozzles communicating with the supply conduit, means to conduct jets of water from the lateral nozzles onto the exterior of the receptacle, a pressure conduit, a flexible partition or diaphragm interposed between the pressure and supply conduits, a pressure chamber above the diaphragm, a throttle valve in the latter having 50 a passage connecting the pressure chamber and pressure conduit to equalize the pressures on both sides of the diaphragm, a spring actuated valve for controlling the pressure chamber, and a receptacle support 55 for actuating said valve.

3. Apparatus for washing open receptacles comprising a funnel, a central nozzle and radial nozzles arranged in the bottom of said funnel, said central and radial nozzles communicating with a feeding conduit 70 of water under pressure, radial grooves provided in the funnel walls, each of said grooves forming an extension of a radial nozzle and having at its upper part a curved projection so that the jet is thrown against 75 the outer surface of the rim of the receptacle to be washed, balls placed in the funnel, openings provided in the funnel walls, to permit the passage of the water but not the balls, a valve normally closed in the conduit 80 feeding the water under pressure and means for opening said valve operated by the receptacle when in the washing position.

4. Apparatus for washing open receptacles comprising a funnel, a central nozzle 85 and radial nozzles arranged in the bottom of said funnel, said radial and central nozzles communicating with a feeding conduit of water under pressure, a support for the receptacle to be washed hinged on one side 90 to the wall of said funnel and on the other side to an actuating member of said valve.

5. Apparatus for washing open receptacles comprising a funnel, a central nozzle and radial nozzles arranged in the bottom 95 of said funnel, said central and radial nozzles communicating with a feeding conduit of water under pressure, radial grooves provided in the funnel walls, each of said grooves forming an extension of a radial 100 nozzle and having at its upper part a curved projection, balls placed in the funnel, openings provided in the funnel walls, adapted to let the water but not the balls pass through them, a chamber in the conduit admitting water under pressure, a flexible partition subdividing said chamber into two superposed compartments, the upper one communicating with a second chamber, while the lower one communicates with the nozzles 110 and contains in its central part a tubular body communicating with the conduit admitting water under pressure, a valve seat arranged at the end of said tubular body, and cooperating with said flexible partition, 115 a capillary conduit placing constantly the conduit admitting water under pressure in communication with the upper compartment, a valve operated by a spring in the second chamber closing the communication 120 of said chamber with the water discharge tube, said valve having a stem projecting in said funnel, a support for the receptacle to be washed hinged on one side to the wall of said funnel and on the other side to the 125 top of the valve stem.

6. Apparatus for washing open receptacles comprising a funnel, a central nozzle and radial nozzles arranged in the bottom of said funnel, said central and radial noz- 130

zles communicating with a feeding conduit of water under pressure, radial grooves provided in the funnel walls, each of said grooves forming an extension of a radial 5 nozzle and having at its upper part a curved projection, balls placed in the funnel, openings provided in the funnel walls, adapted to let the water but not the balls pass through them, an annular tube in the opening through which the receptacle to be 10 washed is introduced in the apparatus, said

annular tube having openings directing a liquid into the interior, a conduit placing said annular tube in communication with the conduit admitting water under pressure, a valve normally closed in the admission conduit and means for opening said valve operated by the receptacle when in the washing position. 15

In testimony that I claim the foregoing as my invention, I have signed my name.

VITTORIO CASOLETTI.
